[57] CLAIM

The ornamental design for a handle for a hostess tray or the like, substantially as shown and described.

DESCRIPTION

FIG. 1 is a top plan view of a handle for a hostess tray or the like showing our new design;

FIG. 2 is a front elevational view;

FIG. 3 is a side elevational view, and

FIG. 4 is a bottom plan view thereof.
